UNITED STATES PATENT OFFICE.

PETER JOHN ANQUIST, OF CHICAGO, ILLINOIS.

FIREPROOF DOOR.

No. 888,863.

Specification of Letters Patent.

Patented May 26, 1908.

Application filed June 3, 1907. Serial No. 376,926.

To all whom it may concern:

Be it known that I, PETER JOHN ANQUIST, a citizen of the United States, and a resident of the city of Chicago, in the county of Cook and State of Illinois, have invented certain new and useful Improvements in Fireproof Doors; and I do hereby declare that the following is a full, clear, and exact description of the same, reference being had to the accompanying drawings, and to the letters of reference marked thereon, which form a part of this specification.

This invention relates to improvements in fireproof doors.

It is an object of this invention to provide a door of the class specified comprising telescoping sections adapted to fold in opening within a suitable space in the wall.

It is also an object of this invention to provide a door in which each section is positively actuated in opening and having a ratio of movement such that all the sections are fully opened or closed simultaneously.

It is further an object of this invention to provide a door in which one of the sections may be opened independent of the opening of the others.

It is finally an object of this invention to provide a very strong door, simple in construction and operation and cheap to install.

The invention relates to the matters hereinafter described and more fully pointed out and defined in the appended claims.

On the drawings: Figure 1 is a front elevation of a vertically opening door with part of the wall in section illustrating the operating mechanism. Fig. 2 is a vertical section of the door shown in Fig. 1. Fig. 3 is a top plan view of the actuating mechanism. Fig. 4 is an enlarged detail of one of the guides and means for engaging the chains to the doors. Fig. 5 is a front elevation of horizontally telescoping doors with part of the wall in section. Fig. 6 is a section on line 6-6 of Fig. 5. Fig. 7 is an enlarged fragmentary front elevation of the actuating mechanism and attaching means. Fig. 8 is a section on line 8-8 of Fig. 5. Fig. 9 is an enlarged top plan view of the mechanism for releasing the independently movable section. Fig. 10 is a side elevation thereof. Fig. 11 is a fragmentary detail of the first section and means for locking the same in closed position.

As shown in the drawings: A indicates the wall of the building which is provided with suitable spaces at the sides and top of the

door opening to receive the operating mechanism and the door therein. The door shown in Figs. 1 to 4 inclusive comprises vertically slideable sections B, B', B² and B³ constructed of sheet metal of any suitable kind and each section having inwardly directed flanges at the top, bottom and ends thereof. The top and bottom flanges are adapted to interlock with the flanges of the section below and above the same and may be integral or constructed of angle irons B⁴ as shown in Fig. 3.

Guide blocks b⁴ are rigidly secured to the flanges at the ends of each section at the top and bottom thereof and fit within the respective guide channels b—b'—b²—b³ provided by the channel bar B⁵ which as shown has inwardly directed parallel partitions B⁶ forming said guide channels.

A shaft D is journaled in the wall at each end of the sections and rigidly secured thereon are sprocket wheels d⁶—d⁷—d⁸ and d⁹. The diameters of each succeeding sprocket wheel increases by the diameter of the first wheel thus affording a ratio of movement such that the second section travels at a velocity of twice the rate of movement of the first section the third at three times the rate, etc. Said sprocket wheels are rigidly secured to rotate together on said shaft and trained therearound are the chains d¹⁰—d¹¹. As shown one end of the chain d¹⁰ is rigidly engaged to the arm d secured to the section B in any preferred manner which extends through a suitable slot in the channel bar B⁵. Said chain is trained over the gear d⁶, around the pulley d⁵, then upwardly over the gear d⁹ and is secured at its lower end to the arm d³, engaged to the section B³. The chain d¹¹ is rigidly secured at one end to the arm d' on the section B' which is trained over the gear d⁷ down around the pulley d⁴, then over the gear d⁸ having the lower end secured to the arm d² engaged to the section B² and a suitable weight is suspended from the pulley d⁴.

For the purpose of actuating the doors a suitable cable C² for manual engagement is trained about sheaves C³ rigidly secured respectively to one of the shafts and to the shaft C' positioned below the same as shown in dotted lines in Fig. 1. Trained about sheaves C one on each of the shafts D is a crossed cable c thus obtaining a positive actuation for each shaft.

The construction shown in Figs. 5 to 10 inclusive comprises sections E, E', E², E³, E⁴,

E⁵, E⁶, and E⁷ four of which telescope and are secured in suitable spaces in the wall on opposite sides of the door opening. Each section is provided with a bracket E⁸ journaled at the corners of which are track wheels e⁴ which are supported on the tracks e—e'—e² and e³ respectively. Suitable guides are provided for the bottom of each section.

The operating connections are practically the same as described with reference to Figs. 10 to 5 with the exception that the end of the chain d¹⁰ is provided with a notched plate f'. A tooth f² on the bracket secured to the section E⁴ normally engages one notch in said 15 plate and a pivotally supported lever F is provided with a tooth at one end adapted to engage in the other notch in said plate. A cord f³ is secured to the opposite end of the lever for manual actuation in elevating the 20 notched plate to clear the tooth f² and a spring f⁴ normally holds the long end of said lever elevated.

The operation is as follows: By actuation of the cable C² in Fig. 1 the shaft D is actuated 25 which operates the sprocket wheels d⁶ to d⁹ inclusive thus imparting simultaneously motion to all of said sections B to B³ inclusive each lower one of which travels at a slightly greater velocity than the adjacent upper section so that when the uppermost section is 30 fully raised and lowered the other sections are also in their respective positions. The weight D' keeps the required tension on said chains permitting free movement of the 35 same. By actuation of the cord or chain f³ the tooth integral with the opposite end of the lever F engages the appropriate notch in the plate f', elevating the plate to disengage the tooth f² on the bracket E⁸ permitting 40 free movement of the section E⁴ so that access may be had through the door without opening all the sections. To return the section E⁴ to normal the lever F is actuated 45 elevating the plate above the tooth f² and the section forced closed when releasing the cord or chain, the spring returns the lever to adjust the plate to engage the tooth on the bracket and the tooth of the lever is depressed below the plate permitting free movement 50 of the sections.

When the plate f' is engaged by the actuating lever F thereby permitting independent opening of the section, said lever holds the other sections closed until the independently 55 opening section has been returned to normal. This is true inasmuch as the plate is held from longitudinal movement by the lever, thus maintaining uniform tension on the chains preventing the sections sliding open.

In Figs. 1 and 2 the guide channels b'—b²—b³ from approximately the bottom of the guide channel b are directed at an outward angle so that the sections are in comparatively the same plane when closed.

65 Instead of chains for actuating the doors

cables and suitable pulleys may be employed and as shown should either of the actuating chains break said doors may be raised by a handle G and the flanges in this case interlocking in closing the door. Also if preferred one of the doors may be provided with a glass panel therein as shown at B, Figs. 1 and 4, and many other changes may be made without departing from the principle of this invention and I therefore do not purpose limiting this application for patent otherwise than necessitated by the prior art. 70 75

I claim as my invention:

1. A fireproof door embracing sections adapted to be concealed within the wall, 80 shafts journaled at each side of the door, differential wheels on each shaft, slotted guides for said sections, arms secured to each section and extending through the slots in the guides, chains or cables secured at its ends to the arms of the end sections and trained around a corresponding number of wheels, the other secured at its ends to adjacent sections and trained around the corresponding wheels, connected pulleys one secured in the 85 bight of each cable or chain, a weight secured thereto, a cable operatively connecting the shafts, a shaft journaled below one of the aforesaid shafts at one side of the door, pulleys on said shafts and a cable trained around 90 the pulleys adapted for manual actuation in opening and closing the door.

2. A door embracing sections, brackets secured to said sections, tracks, wheels on said brackets adapted to support the sections on 100 said tracks, wheels of different diameters journaled at one side of the sections, cables connected with said sections and trained around said wheels, means detachably connecting one end of one cable with its section 105 and means for detaching the cable from said section permitting the same to open independently of the other sections.

3. A device of the class described comprising sections adapted to telescope, means 110 moving said sections at different rates of speed in opening, means for opening one section independently of the other sections and means for returning said opening means to normal position.

4. A door embracing telescoping sections, mechanism for actuating all of the sections simultaneously to open or close the door and mechanism for releasing one of said sections to open independently of the others and 120 firmly securing the remaining sections from opening.

5. A door embracing sliding sections, pulleys journaled adjacent thereto, cables trained around the pulleys adapted at each 125 end to engage the appropriate section, a weight connected with the cables to take up the slack, means detachably securing one end of one of the cables to its respective section, mechanism for actuating said means to per- 130

mit the section to open independently of the other sections and means adapted to automatically return the aforesaid means to engage said section as the same is closed.

5 6. In a door of the class described sliding telescoping sections, mechanism for actuating all the sections to open or close the door, mechanism for releasing one section to open independently of the others and holding the 10 other sections closed until said independently opening section is closed and means returning the releasing mechanism to normal position.

15 7. In a door construction a plurality of tracks, door sections slideable thereon, cables for actuating the sections, weights for keeping the cables taut, manually operated mechanism for releasing one section to open

and holding the other sections closed and means returning said mechanism to normal 20 position.

8. In a device of the class described the combination with tracks of telescoping sections, a bracket on each, wheels thereon adapted to support the section on the appropriate track, means for operating said section at a differential speed and means unlocking one section to open independently of the others.

25 In testimony whereof I have hereunto subscribed my name in the presence of two subscribing witnesses.

PETER JOHN ANQUIST.
